UNITED STATES PATENT OFFICE

WILLIAM E. PAUL, OF SCHENECTADY, NEW YORK, ASSIGNOR TO GENERAL ELECTRIC COMPANY, A CORPORATION OF NEW YORK

ELECTRIC CIRCUIT INTERRUPTER

Application filed September 24, 1931. Serial No. 584,889.

My invention relates to electric circuit interrupters, more particularly to circuit interrupters of the fluid-break type wherein pressure generated by arcing is utilized to 5 interrupt the circuit.

The principal object of my invention is the provision of an improved electric circuit interrupter of the fluid-break type.

My invention will be more fully set forth 10 in the following description referring to the accompanying drawing, and the features of novelty which characterize my invention will be pointed out with particularity in the claims annexed to and forming a part of 15 this specification.

Referring to the drawing, Fig. 1 is a fragmentary elevational view, partly in section, of a circuit interrupter embodying my invention, and Fig. 2 is a similar view of a modified form.

The circuit breaker illustrated by way of example in Fig. 1 is of the well known double-break type wherein a movable bridging member engages similar relatively stationary contact structures to complete the circuit. For 25 the purpose of simplicity therefore but a single pole of the circuit interrupter is shown in detail.

Referring more particularly to the drawing, 30 the bridging member 1 coacts with the relatively stationary contact structures 2 and 3 immersed in an arc extinguishing or insulating liquid 4, as oil. The circuit in each contact structure includes a set of main current interrupting contacts 5 and 6, connected in series with a set of pressure generating contacts 7 and 8. The contact 8 is suitably mounted on and carried by the bridging member 1 forming a conducting part thereof.

The contact housing structure 9 is preferably of insulation and is designed in any suitable manner in order to provide fluid passages and chambers therein as herein-after described. Each housing structure 9 is suitably supported, as by a bolt 12, at the lower end of each insulating bushing 10 through which the lead conductors 11 extend. At the lower part of the housing 9 there is 45 formed a pressure chamber 13 in which the contacts 7 and 8 are arranged to separate,

contact 8 extending through an aperture 14 in the lower wall of the chamber, and contact 7, which is in alignment therewith, extending through a similar opening in the upper wall 15.

The pressure chamber 13 is in communication through a passage 16 with an upper valve chamber 17. The valve 18, controlled in a manner hereinafter described, normally closes an opening 19 in the wall separating 60 the valve chamber 17 from the current interrupting chamber 20 in which the main current interrupting contacts 5 and 6 coact.

The purpose of the contacts 7 and 8 is to generate pressure by the arc formed upon 65 separation of the same, this pressure being utilized to extinguish arcing at the main contacts 5 and 6. The application of this pressure is controlled by the valve 18 which is actuated at or after a predetermined time or 70 in accordance with predetermined opening movement of the switch. In this manner application of arcing pressure may be slightly delayed until it has built up considerably at which time it is released to effect rapid 75 interruption of the circuit. To this end the valve 18 is connected to a piston 21 mounted within the valve chamber 17. The piston 21 is biased, as by spring 22, in a direction to seat valve 18 and close communication be- 80 tween the valve chamber 17 and the interrupting chamber 20. The means controlling operation of the valve comprises a pilot valve 23 normally biased, as by spring 24, to close the opening 25 which affords communication 85 between the rear of piston 21 and the low pressure oil body exterior of the housing structure. The valve stem, which is suitably guided within a bracket 26, is provided at its outer end with a cam portion 27 disposed 90 in the vertical path of a coacting cam member 28 mounted on the lift rod 1'. It is apparent that the pilot valve 23 may be actuated as desired, as by a so-called "zero-selector", i. e., at the moment of current zero, or in ac- 95 cordance with the opening movement of the bridging member 1 as shown.

With pressure existing in the valve chamber 17, opening of the pilot valve 23 immediately reduces the pressure on the correspond- 100

ing side of the piston 21 with the result that the pressure in the valve chamber opens the valve 18 and subjects the insulating liquid in the chamber 20 to the same pressure.

- 5 Interruption of the circuit is caused by separation of the contacts 5 and 6 concurrent with a jet or blast of insulating liquid from the chamber 20 exhausting between the contacts to the outer oil body by reason of the 10 pressure admitted to chamber 20. To this end, contacts 5 and 6 are provided with piston members 29 and 30 respectively, subject to pressure within the chamber 20, and the contacts are mounted so as to separate within a 15 passage 31 exhausting the chamber 20 to the exterior. The pistons 29 and 30 are acted upon by springs 32 and 33 normally biasing the contacts 5 and 6 into engagement. The two sets of contacts 5, 6 and 7, 8 are suitably 20 connected in series, as by a conductor 34 connecting the lead 11 to the contact 5, and conductors 35 connecting the main contact 6 to the pressure generating contact 7.

For the purpose of controlling or limiting 25 the arcing pressure generated, contact 7 is provided with a piston 36 mounted within the housing 9 so that one face is subject to arcing pressure whereas the other face is subject only to low pressure through the opening 37. 30 The piston 36 is biased upwardly by a spring 38 which may be designed in accordance with the operating pressures desired.

The method of operation may be described 35 briefly as follows: Lowering or switch opening movement of the bridging member 1 causes separation of the contacts 7 and 8 with the result that an initial arc is drawn in the chamber 13. At this point it should be understood that the initial arc may be formed 40 by blowing of a fuse in series with contacts 5 and 6 if this construction is preferred. As is well known, the formation of an electric arc in oil generates pressure at a very rapid rate, the rate of increase in pressure depending 45 upon the intensity of the current and length of arc. In order to prevent the arcing pressure from becoming excessive, possibly causing destruction of the contact housing, the differential pressure acting on the piston 36 causes the same to move downwardly so that 50 contact 7 follows contact 8 thereby limiting lengthening of the arc until the contact 8 moves entirely out of the housing.

After or at a predetermined time the pilot 55 valve 23 is opened with the result that the pressure in chamber 17 at once opens the valve 18 due to the greater area of piston 21 and high pressure is immediately communicated to interrupting chamber 20. The pistons 29 and 30 are thereupon forced away 60 from each other against the bias of their springs causing separation of the contacts 5 and 6 while at the same time insulating liquid is exhausted at high velocity through the 65 passage 31 and between the contacts extin-

guishing the arc drawn at these contacts. Since the gas and arc products are formed in the chamber 13 and remain in that region until the valve 18 is opened, it will be apparent that the blast of insulating liquid between the 70 contacts 5 and 6 is substantially unaffected by arc products.

After the blast of insulating liquid between the contacts 5 and 6 has extinguished the arc, the pressure generating arc, being in series 75 therewith, is likewise extinguished so that the pressure within the contact housing is rapidly dissipated. The housings 9 thereupon refill with oil through the various openings so that the apparatus is in readiness for another 80 operation. In the open circuit position the contacts 5 and 6 are again biased into engagement, the current being open through the contacts 7 and 8. The pilot valve 23 may likewise be maintained open so that the space 85 behind the piston 21 is refilled with oil and the valve 18 closed. Closing of the circuit interrupter by upward movement of the bridging member 1 causes engagement of the contacts 7 and 8 and releases the pilot valve 90 so that it is moved onto its seat.

When the circuit interrupter must have high current-carrying capacity, so-called primary contacts are employed to shunt the main part of the current around the secondary or 95 arcing contacts. This general arrangement which is well known in the art is shown in Fig. 2, the movable primary contacts 39 being connected to the extremities of the lift rod. The contacts 39 coact with the stationary primary contacts 40 which are electrically connected to the lead-in conductors 11 in any suitable manner as by the conductors 40'. The primary contacts are of the well-known wedge and finger type and do not require 100 further description. The arrangement is such that the primary contacts are separated a predetermined distance before possible interruption of the circuit since otherwise destructive arcing might occur at the primary 110 contacts.

When a bridging circuit including primary contacts is used in connection with my invention, it is possible to reduce the time required 115 to interrupt the circuit by reason of the separately movable pressure generating contacts. For the purpose of keeping the contacts 7 and 8 in engagement until separation of the primary contacts 39 and 40, a resilient connection or "wipe" between the contact 7 and piston 36 is provided comprising a spring 41 which is located between the piston 36 and a shou'der 42 forming part of the contact 7. In this case the piston 36 is mounted for relative movement with respect to the contact 7. 120 When the bridging member 1 descends, the "wipe" or overtravel at the contacts 7 and 8 permits opening of the primary contacts prior to separation of the arcing contacts so that 125 the entire current is shunted through the arc- 130

- ing contacts. Immediately after the primary contacts have separated, the pressure generating arc is formed by separation of the contacts 7 and 8. Since the actual resistance of the arc is quite small, the formation of the pressure generating arc at once does not increase the voltage across the interrupter terminals so that there is little danger of arc-ing-over at the separating primary contacts. 5
- 10 The arcing pressure may thereupon build up until the primary contacts have separated a predetermined distance, at which time the valve 18 is opened as illustrated and the circuit at the contacts 5 and 6 immediately interrupted by the high velocity oil blast through the interrupting chamber 20. In this manner the interrupting time is reduced to a minimum and arcing at the primary contacts is precluded since interruption of the circuit 15 does not occur until the primary contacts are separated a safe distance. The apparatus is shown in Fig. 2 at the moment of circuit interruption, the primary contacts 39 and 40 being a safe distance apart so that the oil blast is effective to interrupt the circuit. 20
- 25 In certain cases it may be desirable to eliminate the valve 18 so that there is direct communication between the interrupting chamber and pressure generating chamber. This arrangement need not involve appreciable change in design of the housing other than possible closer spacing of the chambers.
- 30 It should be understood that my invention is not limited to specific details of construction and arrangement thereof herein illustrated, and that changes and modifications may occur to one skilled in the art without departing from the spirit of my invention.
- 35 What I claim as new and desire to secure by Letters Patent of the United States, is:
1. A circuit interrupter of the fluid-break type comprising a pair of contacts separable in an arc extinguishing liquid to form a pressure generating break connected in series with a pair of independent and separately movable current interrupting contacts, and means for directing pressure generated by arcing at said break so as to cause separation of said independent current interrupting contacts 40 and force a blast of insulating liquid between the same extinguishing arcing.
  2. A circuit interrupter of the fluid-break type comprising two independent sets of separately movable contacts connected in series immersed in an arc extinguishing liquid, one set of contacts forming an initial pressure generating arc, and means directing said pressure so as to separate the other set of contacts and force a jet of insulating liquid between the same extinguishing arcing. 45
  3. A circuit interrupter of the fluid-break type comprising two independent sets of separately movable contacts connected in series immersed in an insulating liquid, one of said sets forming an initial pressure generating 50
  4. A circuit interrupter of the fluid-break type comprising a plurality of independent sets of separately movable contacts connected in series and immersed in insulating liquid within separate chambers, one of said sets forming in one chamber a pressure generating arc, means directing said pressure into another chamber causing interruption of arcing at another set of said contacts, and a valve controlling communication between said chambers. 55
  5. A circuit interrupter of the fluid-break type comprising two sets of contacts connected in series immersed in insulating liquid, one of said sets forming a pressure generating arc, means directing said pressure so as to cause separation of and interruption of arcing at the other set of said contacts, and a valve controlling and delaying the application of said pressure. 60
  6. A circuit interrupter of the fluid-break type comprising a pair of main current interrupting contacts connected in series with a pair of independent and separately movable pressure generating contacts, said contacts immersed in an insulating liquid, means directing pressure generated at said last named contacts so as to cause separation of said main contacts and force a jet of insulating liquid between the same, a valve controlling application of said pressure to said main contacts, and means controlling actuation of said valve in accordance with circuit opening movement. 65
  7. A circuit interrupter of the fluid-break type comprising means forming a pressure generating break in an insulating liquid, circuit interrupting means connected in series with said break, and means controlling pressure generated by arcing at said break including a valve opened by said pressure, said valve admitting a blast of insulating liquid to said circuit interrupting means. 70
  8. In a circuit interrupter of the fluid-break type including primary current carrying contacts, arc extinguishing means comprising circuit interrupting means and contacts forming a pressure generating arc immediately after separation of said primary contacts, said pressure tending to cause a blast of insulating liquid across the arc formed at said circuit interrupting means, and a valve releasing said pressure to cause interruption of the circuit only when said primary contacts are separated by a distance precluding arcing. 75
  9. A circuit interrupter of the fluid-break type including pressure generating means within an insulating liquid and coating con- 80

tacts between which insulating liquid is forced by said pressure interrupting the circuit, means controlling application of said pressure comprising a valve actuated by said pressure, and a pilot valve reducing the pressure on one side of said valve causing opening thereof.

10. A circuit interrupter of the fluid-break type comprising contact housing structure immersed in an insulating liquid, relatively movable contacts forming a pressure generating arc within a chamber in said housing, said pressure tending to force insulating liquid through a second chamber and 15 between coating contacts therein to interrupt the circuit, a valve mounted within said housing controlling communication between said chambers, a pilot valve controlling the opening of said valve by said arcing pressure, 20 and cam structure related to said movable contact opening said pilot valve after predetermined circuit opening movement.

In witness whereof, I have hereunto set my hand.
